PROCESS OF HEAT CONTROL IN CATALYTIC HYDROGENATION REACTIONS

Bernard J. C. Van der Hoeven, Beaver, Pa., assignor to Koppers Company, Inc., Pittsburgh, Pa., a corporation of Delaware

Application September 20, 1946, Serial No. 698,381

7 Claims. (Cl. 260—667)

1

This invention relates to heat control in catalytic hydrogenation reactions, and is more particularly directed to the application of novel heat control methods in processes for vapor phase catalytic hydrogenation of aromatic compounds, especially in the manufacture of cyclohexane by vapor phase catalytic hydrogenation of benzene.

Many catalytic hydrogenation reactions such as the vapor phase hydrogenation of aromatics such as benzene and naphthalene and their derivatives and homologues are strongly exothermic and require some form of heat control to keep the catalyst within its effective range of hydrogenation temperature. Close control of temperature requiring the rapid removal of large quantities of heat from the catalyst is required in order to avoid development of hot spots which cause excessive deterioration of the catalyst and in order to avoid objectionable side reaction which degrade the desired product.

Various methods for controlling the temperature of the catalyst in hydrogenation catalysis have been suggested and/or utilized in the prior art. These usually involve a heat exchange type converter of suitable design using such heat transfer media as water under pressure, mercury, sulfur, and like heat transfer fluids. The present invention does not differ from the prior art in this respect but as will appear more particularly hereinafter utilizes such heat transfer fluid to remove the heat of catalysis from the catalyst.

The difficulty with the prior art methods is that no matter how effective a heat transfer medium is employed, the maximum efficiency of the heat exchange type converter is limited by the rate at which heat may be dissipated from the catalyst, which is not very great considering the low thermal conductivity of the common carriers used in hydrogenation catalysts. It has been necessary, therefore, in accordance with the prior art practices to utilize heat exchange type converters having small tubes; say about 1 inch or less in diameter, or similarly constructed heat exchange converters in which the catalyst is so distributed with reference to the heat transfer fluid that the heat of catalysis need only travel through a small layer of catalyst to reach the heat transfer fluid. Thus it has been necessary in the prior art to utilize especially designed equipment to accommodate the peculiar heat conditions in a hydrogenation catalysis.

The present invention has for its objects to provide novel methods of temperature control in vapor phase catalytic hydrogenation reactions, to provide efficient means for dissipating the heat

2

of the reaction in such processes, to provide simple and effective processes for making cyclohexane by the catalytic hydrogenation of benzene, to provide processes in which the size and distribution of the catalyst mass is relatively non-critical, to avoid the disadvantages of the prior art and to obtain advantages as will become apparent as the description proceeds.

These objects are accomplished in the present invention by carrying out the catalysis with a procatalysate consisting predominantly of inerts. By carrying out the catalysis with a procatalysate consisting predominantly of inerts, of example, a procatalysate consisting essentially of prohydrogenate vapor and hydrogen in hydrogenating proportions in admixture with an inert gas in the proportion of at least 2 mols or volumes of inert gas for each mol or volume of prohydrogenate vapor, I am able to obtain effective hydrogenation catalysis in processes in which the size and distribution of the catalyst mass is such that the heat transfer rate within the catalyst mass is insufficient to carry off the heat of catalysis when the catalysis is carried out without the inert gas or with at most a minor proportion thereof.

In describing the invention the term "prohydrogenate" will be used to refer to the material which is hydrogenated, the term "hydrogenate" to the material produced, the term "procatalysate" to the material fed to the converter, the term "catalysate" to the material effluent of the converter and the term "catalants" to the materials involved in the conversion. Thus in the hydrogenation of benzene, benzene is the prohydrogenate, cyclohexane is the hydrogenate, the mixture of benzene, hydrogen and inert gas is the procatalysate, the mixture of cyclohexane, hydrogen, etc. effluent of the converter is the catalysate and the benzene and hydrogen are the catalants.

While it has heretofore been determined that the rate of hydrogenation of benzene is inversely proportional to the amount of cyclohexane vapor present when suitable mixtures are passed through a thin layer of catalyst at atmospheric pressure (C. A. 37, 4614 (1943)), the present invention does not depend entirely for its efficacy upon a lowered rate of hydrogenation per se, but produces results entirely disproportionate thereto. The processes of the present invention, moreover, are conducted at superatmospheric pressure to inhibit the reverse reaction which is largely responsible for the effects noted in this reference.

When procatalysate, properly constituted and proportioned in accordance with the invention, is passed in the vapor phase at superatmospheric

pressure through an elongated catalyst mass, that is to say, a mass the length of which is at least about four times its minimum transverse dimensions, in contradistinction to a thin layer, there is obtained, in addition to a lowering of the velocity of the reaction, an unexpected increase in the heat transfer efficiency within the catalyst mass. By virtue of this increased heat transfer efficiency, it is possible, in accordance with the invention, to use much larger masses of catalyst than was possible in the prior art. As the volume of gas, which passed through the catalyst mass per unit of hydrogenate produced, is increased by dilution with an inert gas, a critical velocity is obtained in the catalyst mass at which the heat transfer efficiency is significantly increased. This effect is significant when the major portion of the procatalysate is an inert gas and becomes marked when the dilution reaches 2 or more mols or volumes of inert gas for each mol or volume of prohydrogenate vapor and increases exponentially as the rate of throughput is further increased by further dilution.

It is possible, therefore, in accordance with the invention, to utilize heat exchange converters having substantially larger tube diameters and substantially larger cross sectional area of catalyst through which heat must be dissipated to the heat transfer fluid than in the prior art methods. Thus the present invention makes it possible to utilize heat exchange converters of simpler and more economical design. Moreover, the processes of the invention are readily adaptable to a wide variety of heat exchange converters making it possible to utilize stand-by equipment even though not especially designed for hydrogenation catalysis in accordance with the prior art methods.

The invention may be more fully understood from the following detail description taken with reference to the accompanying drawing in which Figure I is a flow sheet of a simplified form of the invention, Figures II and II are curves illustrating qualitatively certain aspects of the invention, Figures IV and V are flow sheets illustrating typical embodiments of the invention and Figure VI is a detailed view of a modified form of Figure III.

While the invention is applicable to hydrogenation catalysis of a wide variety of materials such as benzene, toluene and like hydrocarbons of the benzene series; naphthalene, methyl naphthalene and like hydrocarbons of the naphthalene series; phenol, cresols, naphthals, etc.; and olefins where the heat of the reaction is big enough to be a problem, and particularly aromatic hydrocarbons, it is most suitably illustrated with reference to hydrogenation of benzene. Such a process and apparatus suitable for carrying it out are illustrated diagrammatically in Figure I. The process is carried out as follows:

Benzene and cyclohexane are mixed in the desired proportions in supply tank 2, elevated to the operating pressure and temperature by pump 4 and heater 6, and then passed through line 8 to converter 10. Simultaneously, hydrogen is elevated to the operating pressure and temperature by compressor 12 and heater 14 and passed through line 16 to the converter 10.

The operating pressure is determined as that best suited to suppress the reverse reactions. With benzene a pressure of 75 pounds per square inch gauge is sufficient and any higher pressure within the limits of practicability may be used. Lower pressures, though preferably not lower

than about 50 pounds per square inch gauge, may be used since any pressure above atmospheric tends to suppress the reverse reaction. Where cyclohexane is used as the diluent, it is important that a pressure above about 50 pounds and preferably at least about 75 pounds per square inch gauge be used because otherwise the yield may be adversely effected by the reverse reaction on the recycled cyclohexane. At pressures of about 75 pounds per square inch gauge or more, the reverse reaction is not significant. With other prohydrogenates higher pressures may be required substantially to suppress the reverse reaction. Those skilled in the arts, having in mind these principles, will readily be able to determine what pressures are required in any particular case to effect substantial suppression of the reverse reaction.

The converter 10 consists of a 3 inch pipe or tube 18 surrounded throughout the major portion of its length by a water jacket 20. In the bottom of tube 18 there is provided a catalyst support 22 projecting upwardly to a point several inches above the bottom of the water jacket 20. The tube 18 is packed with catalyst pellets, as shown by the hatching, to within a few inches of the top of water jacket 18, and the over-all dimensions are such to provide a catalyst mass 3 inches in diameter and 84 inches long.

Temperature regulation in the converter is obtained by circulating a suitable heat transfer fluid such as water under pressure, or Dowtherm, through the water jacket 20. The heat transfer fluid is withdrawn through lines 24 and 26 to the cooler heater 28 through reservoir 30 or by-pass 32 and returned to the water jacket 20 through lines 34 and 36 by means of pump 38. Make-up water is introduced into reservoir 30 by means of pump 40 and maintained at the desired operating pressure; for example, at about 200 pounds per square inch gauge. The reservoir 20 which serves as an expansion tank is not needed when Dowtherm is used. Hence, when Dowtherm is used as the heat transfer fluid, valve 42 and 44 are closed and valve 46 opened to by-pass the reservoir. Cooling water or steam may be used to heat or cool the heat transfer fluid in the cooler-heater 28.

The effluent of the converter 10 is passed through line 48 to condenser 50 and the condensate is collected in the product receiver 52. Hydrogen and other non-condensables, for example, methane, are vented at 54.

Operation of the described process under a wide variety of conditions within the scope of the invention is illustrated in the following tables: The data of Table I were obtained using water as a heat transfer fluid; whereas the data of Table II were obtained by using Dowtherm. In each case the procatalysate mixture containing benzene in the indicated proportion (parts are by weight throughout the specification except where otherwise specified), a 50% excess of hydrogen and the balance, cyclohexane, was passed through the elongated catalyst mass at the indicated space velocity while maintaining the catalyst mass within its effective temperature range by circulating the heat transfer fluid through the jacket 20 at the indicated temperature.

The catalyst was reduced nickel mounted on kieselguhr. It is suitably prepared as follows: Nickel carbonate-kieselguhr is precipitated by adding sodium carbonate to nickel sulphate plus kieselguhr. The approximate composition of the nickel compound in the catalyst powder is $2\text{NiCO}_3 \cdot 7\text{Ni(OH)}_2 \cdot 7\text{H}_2\text{O}$, assuming that the kiesel-

5
guhr is water free. The powder is mixed with 4% of graphite and fabricated in the form of $\frac{1}{8}$ " diameter by $1\frac{1}{12}$ " thick pills. The pills thus prepared and before reduction are known as "green catalyst." The green catalyst is decarbonated and reduced with hydrogen at 425° C. It is then stabilized by superficial oxidation with air at the same temperature. The stabilized catalyst pellets are then passed in the converter tube 18 and given a further reduction with hydrogen at 200° C. at atmospheric pressure.

6
fied, the percentage of benzene is determined by the "Acid Heat Test" in which the amount of benzene present is correlated with the heat of nitration by an empirical curve. This test usually indicates a slightly higher purity than the freezing point method; however, at purities of 99%, the difference is usually not more than 0.2%. Under conditions of comparable and continued operations the cyclohexane would pass through the converter five or six times and consequently the impurities would not exceed 1.25 to 1.5%.

L	25.0	11.1	80	1.060	4.40	153	192	292	18-24	98.9	

The data given in the above tables show efficient operation over a wide range of conditions. They show that the space velocity, figured as volumes of liquid per volume of catalyst per hour, may be varied over a wide range without adversely effecting the operation, thus the benzene space velocity was varied from 0.18 to 1.06 and the total liquid space velocity was varied from about 2 to a little over 7.5. This great flexibility operation is characteristic of the processes of the invention and is apparently due to the fact that, within the proportions which, as pointed out above, are critical to the invention, increases or decreases in throughput are largely compensated by corresponding increases or decreases respectively in the heat transfer coefficient in the catalyst mass due to the corresponding increase or decrease in the mass velocity of the gases passing therethrough. Under comparable conditions without a diluent gas, the maximum practical tube diameter is around 1 in. With larger diameter tubes the temperature in the catalyst mass becomes excessive. Efforts to carry out the reaction in $1\frac{1}{2}$ in. tubes without a diluent gas proved unfeasible because of fusion in the catalyst mass.

It was determined also under comparable conditions that cyclohexane could be recycled without objectionable build-up of impurities due to decomposition or isomerization of the cyclohexane. Thus, starting with a feed mixture containing 18.25% benzene and the balance cyclohexane of 99.65% purity and recycling product cyclohexane, it was determined that after two passes the purity dropped to 99.25%, after four passes to 98.9%, after 6 passes to 98.65%, and after 8 passes to 98.45% as determined by the freezing point method. In Figure II there is shown a curve illustrating the relation between the feed composition and the permissible tube size. The data is figured on the basis of an 84" catalyst bed with a rate of throughput sufficient to hydrogenate 2 gallons of benzene per hour. For a 3 inch tube this figures to be a liquid hourly space velocity of 0.78 volume of benzene per volume of catalyst per hour. The curve shows that within the limits of the invention; i. e. about 30% or less of benzene, there is a significant increase in the size of the tube which may be utilized in the process. The approximate weight percentages of cyclohexane, the diluent, are also given opposite the weight percentages of the benzene from which proportions may be determined. Since these are determined on the basis of 50% excess hydrogen, the proportions by weight do not differ significantly from the proportions by volume, or in other words from the molar proportions. Thus for 30% benzene the weight proportion is 2.2 parts of cyclohexane for each part of benzene, whereas the mol proportion is 2.1 mols of cyclohexane for each mol of benzene.

Figure III plots the second derivative of the curve of Figure II, or in other words, the first derivative of the slope of the curve of Figure II, and therefore represents the rate of change of slope of the curve of Figure II. It shows that the rate of change of slope reaches a maximum at about 30% benzene, the point where critical effect of the diluent becomes marked.

From inspection of the curves of Figures II and III it will be seen that the permissible tube size increases very slowly as cyclohexane is added to the procatalysate down to about 30% benzene and that thereafter the permissible tube size increases very rapidly. It is thus possible to oper-

ate in accordance with the invention with converters having tubes significantly larger than heretofore considered practical in the prior art.

Another advantage of operating within the limits of the invention which is not apparent from the curve but which is amply illustrated in the data given in Figures I and II is that within the limits of the invention, tube size is substantially less critical than in the prior art processes. Thus while the curve of Figure I shows that a benzene concentration of 15% is most desirable for a 3 inch tube and a benzene space velocity of 0.78 the data of Tables I and II show great flexibility of operation over the range of 10 to 25% benzene. If the weight percent of benzene were held constant, say at 15%, it would be possible to effect a correspondingly wide variation in the tube size. Of course, any tube less than 3 inches in diameter could be used. A larger tube can also be used, depending upon the efficiency of the heat transfer fluid and the rate of throughput and the desired conversion of benzene to cyclohexane as well as other factors such as depth of catalyst bed, activity of catalyst, etc. All things being equal, increased rate of throughput gives lowered temperatures in the catalyst mass, and consequently better heat control. Thus heat control in the catalyst mass may be regulated by regulating the rate of throughput up to the point where conversion of benzene to cyclohexane is inadequate. Thus, with benzene content less than 30% in the procatalyst it is possible to utilize tubes of 1½ inches in diameter or more up to 5 inches in diameter or more, whereas in the prior art method it was not feasible to use a tube as large as 1½ inches in diameter.

The invention may be more fully understood with reference to particular embodiments thereof by referring to the flow sheets illustrated in Figures IV, V and VI. These flow sheets illustrate diagrammatically apparatus suitable for carrying out processes in accordance with the invention in simple and economical manner.

The apparatus illustrated in these figures consists essentially of a heat exchange converter 56, a vaporizer 58, a condenser 60, and a means for circulating fluids appurtenant to the process. The heat exchange converter may be of conventional design such as the multiple tube heat exchange converter illustrated at 56. The tubes of the converter are packed with catalyst throughout a substantial portion of their length so that prohydrogenate vapor in passing through the tubes passes through an elongated mass of catalyst. Suitable means including lines 62 and 64 are provided for circulating a heat transfer fluid about the tubes of the converter in order to maintain the catalyst mass in the tubes within its effective range of temperature.

Heat transfer fluid from converter 56 is passed through line 64 into vaporizer 58 where at least a part of the heat absorbed from the catalyst is utilized to vaporize liquid prohydrogenate and, if desired, liquid hydrogenate. The heat transfer fluid is withdrawn from the vaporizer 58 through line 66 and circulated by means of pump 68 through the heater cooler 70 and/or by-pass 72 to line 62 to complete the cycle of heat transfer fluid. The heater cooler 70 is so designed that it may be used as a heater during the start-up period when it is necessary to bring the catalyst to a temperature within its effective range of temperature. By suitable regulation of valves 74 and 76 the extent of the heating and/or cool-

ing effected in converter 56 may be simply and effectively controlled.

In carrying out processes according to the invention and illustrated in Figure IV, liquid prohydrogenate is brought to the operating pressure characteristic of the particular hydrogenation catalysis by means of a suitable pump 78 and passed through line 80 into vaporizer 58 where it is vaporized by indirect heat exchange with the catalysis through the instrumentality of the heat transfer circuit described above. Simultaneously hydrogen at the operating pressure and in hydrogenating proportion to the liquid prohydrogenate is brought into admixture with the prohydrogenate vapors. Intimate admixture is advantageously obtained by bringing the hydrogen through line 82 into the bottom of the vaporizer 58. Part of the required hydrogen is recycled hydrogen as will be more particularly described and the remainder from any suitable source is elevated to the operating pressure by means of a suitable compressor 84 and introduced into the system by line 86.

The effluent of the vaporizer 58 passes through line 88 into the heat exchange converter 56 where the catalysis is effected. Heat of catalysis is transferred to the heat transfer fluid and in turn transformed to heat of vaporization in the vaporizer 58 and/or dissipated in the condenser 60 and cooler 70.

The mixture of hydrogenate vapor and hydrogen effluent of the converter 56 is divided into two portions; one portion, the quantity of which is determined by the setting of valve 90, is recycled by means of pump 92 through line 94 back to line 82, thus completing a cycle and the remaining portion is condensed in condenser 60 and collected in receiver 96. Part of the condensate of receiver 96 may be recycled if desired through lines 98 and 100 by means of pump 102 to line 80 thus completing a cycle.

Suitable means for reducing the pressure is provided at 104 or, if desired, in line 106 and vent 108.

According to this form of the invention it will be seen that the hydrogenate required as a diluent for the reactant may be recycled either in the vapor phase or in the liquid phase, though a more suitable system for accomplishing the latter is illustrated in Figure V which will be subsequently described. According to the form of the invention shown in Figure IV it is contemplated that the major portion, if not all of the recycled hydrogenate is recycled in the vapor phase. This has the advantage of simultaneously recycling the bulk of the excess hydrogen as well as materially reducing the load on condenser 60. Since it is desirable that the feed mixture shall contain at least 2 mols or volumes of hydrogenate for each mol or volume of prohydrogenate as more fully set out above, it follows that at least ½ of the hydrogenate effluent of the converter 60 must be recycled. By recycling all, or substantially all, of this in the vapor phase, a very marked reduction in the load on the condenser 60 is effected. This makes it possible to use a condenser of a much smaller capacity than if all of the hydrogenate effluent of converter 56 were to pass through the condenser, and has the advantage that it is cheaper to dissipate heat of a reaction in an ordinary cooler such as is contemplated at 70 than in a condenser.

It is desirable, according to one form of the invention, that the condenser 60 shall have inadequate capacity to condense all of the hydro-

genate effluent of the converter 56 and that at least the hydrogenate in excess of the condenser capacity be recycled in the vapor phase as described. Moreover, by recycling at least $\frac{2}{3}$ of the hydrogenate effluent of the converter 56 while in the vapor phase, most of the excess hydrogen is recovered and the balance which passes uncondensed through condenser 60 is vented through line 108 in order to purge the system of any by-product gasses which are formed as a result of the hydrogenation catalysis.

As above noted, Figure V illustrates a process in which the recycled hydrogenate may advantageously be recycled in the liquid phase. The general arrangement of the apparatus is the same as in Figure IV and like reference numerals are used to designate like parts. The principal difference lies in the method of recycling excess hydrogen and the recycled hydrogenate.

The mixture of hydrogenate and hydrogen effluent of converter 56 is passed through the condenser 60 into high pressure receiver 110 where a separation between the condensed hydrogenate and noncondensables, including excess hydrogen, is effected. The noncondensables are passed through lines 112 and 114 by means of a pump 116 back to line 82, thus completing a cycle whereby excess hydrogen is recovered. A portion of the noncondensables is vented through reducing valve 118 in order to purge the system of any gaseous by-products of the catalysis.

The liquid hydrogenate from receiver 110 is divided into two portions, one of which is passed through reducing valve 120 into low pressure receiver 122 as product, and the other of which is passed through lines 98 and 100 by means of pump 102 to line 80, thus completing a cycle. If desired, a portion of the mixture of hydrogenate and excess hydrogen may be bled off through valve 124 and line 126 to the inlet side of pump 116.

It will be observed that in accordance with this form of the invention, substantially all of the recycled hydrogenate is recycled in the liquid phase. This has the advantage of increasing the proportion of the heat of catalysis which is transformed to heat of vaporization in the vaporizer 58, and in fact, under ideal conditions, the proportion of hydrogenate recycled as liquid to the liquid prohydrogenate may be such that all of the heat of catalysis in excess of normal losses may be transformed into heat of vaporization. When the desired proportion of hydrogenate to prohydrogenate is such that the heat of catalysis is not sufficient to effect vaporization of both, part of the recycled hydrogenate may be recycled in the vapor phase through line 126, or the cooler-heater 70 may be operated as a heater to supply the necessary heat. Operation in this manner has the advantage that only one piece of apparatus, namely the condenser 60 is required to effect dissipation of the heat of catalysis. This provides simplicity and flexibility of operation. For example, with adequate cooling capacity in the condenser 60, valve 76 may be closed off completely so as to by-pass the cooler-heater 70 and temperature control in the process effected by suitable adjustments in valves 124 and 128.

How this type of control may be still further simplified is illustrated in Figure VI where separate condensers 60-A and 60-B are utilized to condense the recycled hydrogenate and the product hydrogenate respectively. By suitable adjustment of valves 130 and 132 the proportion

of recycled hydrogenate to product hydrogenate is determined. Thereafter, all that is necessary to effect temperature regulation in the process is to adjust the setting of valve 124-A which may be done either manually or by suitable automatic control devices.

The form of the invention illustrated in Figure V is further of advantage in that it is well adapted to the use of an inert gas such as nitrogen for the diluent for the prohydrogenate. Nitrogen may be introduced along with the hydrogen or separately by a suitable compressor, not shown, to take the place of recycled hydrogenate. It is then separated from the hydrogenate in condenser 60 and high-pressure receiver 110 and recycled through lines 112 and 114 back to line 82. The amount of nitrogen which need be introduced into the process initially will be that required to give at least two volumes of nitrogen in the effluent in the vaporizer 58 to each volume of prohydrogenate vapor. Thereafter the amount which need be introduced will correspond to the amount vented at 118 and need be only sufficient to purge the system from accumulations of uncondensable gases formed in the catalysis.

Unless otherwise specified the parts are by weight and pressures are in pounds per square inch gauge.

While I have described my invention with reference to particular embodiments thereof it is to be understood that they are given by way of illustration only and that variation may be made therein without departing from the spirit and scope of the invention as described herein and set forth in the appended claims. Thus while I have described my invention with reference to vapor phase hydrogenation and while the effects of diluent hydrogenate are especially pronounced in vapor phase hydrogenations, nevertheless some of the objects of the invention are accomplished in liquid phase hydrogenation where the catalysis is effected in the presence of a major proportion of hydrogenate and at a pressure above atmospheric sufficient substantially to suppress the reverse reaction.

I claim:

1. In a process for vapor phase hydrogenation catalysis in a single stage heat exchange converter of the jacketed type wherein a heat transfer fluid is circulated through said jacket in contact with the walls of the catalyst-containing units in indirect heat exchange through said walls with the catalyst therein and to and from means for regulating the temperature of the heat transfer fluid and wherein the transverse dimensions of the catalyst mass in each said unit are not substantially less than $1\frac{1}{2}$ inches and not substantially greater than 5 inches and the length of said catalyst mass in each said unit is at least four times the minimum transverse dimensions, whereby the distance heat of catalysis has to travel through the catalyst mass to reach said walls is so great that overheating of the catalyst mass results when the procatalysate consists essentially of prohydrogenate and hydrogen in hydrogenating proportions, the improvement which comprises preparing a gaseous mixture consisting essentially of prohydrogenate vapor and hydrogen in hydrogenating proportions in admixture with a recycled inert gas in the proportions of at least 2 mols and less than 10 mols of inert gas for each mol of prohydrogenate, passing said gaseous mixture through said catalyst mass at a rate which gives substantially complete conversion and at a pressure sufficient

11

to suppress dehydrogenation of the product while maintaining said catalyst mass within its effective range of temperature primarily by regulating temperature of said heat transfer fluid.

2. The process of claim 1 in which the prohydrogenate is benzene and the recycled inert gas consists essentially of cyclohexane.

3. The process of claim 2 in which the rate of throughput is between about 2 and 7.5 liquid volumes of benzene and cyclohexane per volume of catalyst per hour.

4. The process of claim 1 in which liquid prohydrogenate and liquid hydrogenate are vaporized by indirect heat exchange with the heat transfer fluid to provide in part said gaseous mixture and in which the quantity of liquid thus vaporized is such that the heat of vaporization substantially equals the amount of heat of catalysis transferred to the heat transfer medium.

5. The process of claim 4 further characterized in that the catalyst is divided into two streams, the first of which contains hydrogenate in an amount substantially equivalent to the prohydrogenate, the hydrogenate of this stream is condensed as product, the second stream is divided into third and fourth streams, the third stream is recycled to the catalysis without substantial

change in temperature and pressure as part of the recycled inert gas, the hydrogenate of the fourth stream is condensed and returned to the evaporating step to provide the balance of the recycled inert gas whereby the temperature of the heat transfer fluid may be regulated by adjusting the relative flow of catalyst in the third and fourth streams.

6. The process of claim 4 in which the prohydrogenate is benzene and the recycled inert gas consists essentially of cyclohexane.

7. The process of claim 6 in which the rate of throughput is between about 2 and 7.5 liquid volumes of benzene and cyclohexane per volume of catalyst per hour.

BERNARD J. C. VAN DER HOEVEN.
